Fig. 4

Fig. 5

Fig. 6

Fig. 7

Fig. 8

Fig. 9

Fig. 10

FIGURE 1 is a front perspective view of a bleacher showing my new design wherein the over all length is comparatively short and only a pair of upright members are utilized;

FIGURE 2 is an end elevation thereof as viewed from the left hand side of FIGURE 1, this view also being typical of the opposite end of the bleacher in FIGURE 1;

FIGURE 3 is a top plan view of the unit shown in FIGURE 1 with the top of the unit in FIGURE 3 constituting the rearward and upper portion of the bleacher;

FIGURE 4 is a front elevational view of the unit shown in FIGURE 1;

FIGURE 5 is a rear elevational view of the unit shown in FIGURE 1;

FIGURE 6 is a front perspective view of a bleacher showing my new design wherein the over all length is comparatively elongated and a plurality of upright members are utilized;

FIGURE 7 is an end elevation thereof as viewed from the left hand side of FIGURE 6, this view also being typical of the opposite end of the bleacher in FIGURE 6;

FIGURE 8 is at top plan view of the unit shown in FIGURE 6 with the top of the unit in FIGURE 8 constituting the rearward and upper portion of the bleacher;

FIGURE 9 is a front elevational view of the unit shown in FIGURE 6; and

FIGURE 10 is a rear elevational view of the unit shown in FIGURE 6.

I claim:

The ornamental design for a bleacher, substantially as shown.
